UNITED STATES PATENT OFFICE

RICHARD C. WOLFE, OF BEVERLY HILLS, CALIFORNIA, ASSIGNOR TO CALIFORNIA CONSOLIDATED WATER COMPANY, OF LOS ANGELES, CALIFORNIA, A CORPORATION OF DELAWARE

DESIGN FOR A WATER COOLER

Application filed January 16, 1932. Serial No. 42,515. Term of patent 14 years.

To all whom it may concern:

Be it known that I, RICHARD C. WOLFE, a citizen of the United States, residing in Beverly Hills, county of Los Angeles, State of California, have invented a new, original, and ornamental Design for a Water Cooler, of which the following is a specification, reference being had to the accompanying drawings, forming part thereof.

In the drawings:

Fig. 1 is a front elevation;
Fig. 2 is a side elevation; and,
Fig. 3 is a top plan view of a water cooler showing my new design.

I claim:

The ornamental design for a water cooler, as shown.

Signed at Los Angeles, California, the 4th day of January, 1932.

RICHARD C. WOLFE.
